AUTOMATIC COPY SHEET FEEDER FOR COPIERS

Ohiko Yagi and Toshio Shiina, Yokohama, Japan,
assignors to Kabushiki Kaisha Ricoh, Tokyo, Japan

Filed May 14, 1973, Ser. No. 360,380

Term of patent 14 years

Int. Cl. D16—04

U.S. Cl. D61—1 Q

FIG. 1

FIG. 2

FIG. 3

FIG. 4

FIG. 5

FIG. 6

FIG. 7

FIG. 1 is a front, top and right side perspective view of an automatic copy sheet feeder for copiers showing our new design;

FIG. 2 is a top plan view thereof;

FIG. 3 is a front elevational view thereof;

FIG. 4 is a right side elevational view thereof;

FIG. 5 is a rear elevational view thereof;

FIG. 6 is a left side elevational view thereof; and

FIG. 7 is a bottom plan view thereof.

We claim:

The ornamental design for an automatic copy sheet feeder for copiers, as shown.
